UNITED STATES PATENT OFFICE.

JAMES M. NEIDIG, OF HARRISBURG, PENNSYLVANIA.

MULTIPLE-FUSE PLUG.

Application filed July 7, 1922. Serial No. 573,322.

To all whom it may concern:

Be it known that I, JAMES M. NEIDIG, a citizen of the United States, and a resident of Harrisburg, in the county of Dauphin 5 and State of Pennsylvania, have invented new and useful Improvements in Multiple-Fuse Plugs, of which the following is a full, clear, and exact description.

This invention relates to multiple fuse 10 plugs.

The general object of the invention is the provision of a cheap, simple and efficient fuse plug containing more than one fuse so that when one fuse is blown the other 15 may be utilized to replace it.

A further object of the invention is the provision of a multiple fuse plug divided into two compartments by means which allows the gases, formed by the blowing of 20 a fuse, to expand throughout the two compartments, thus giving a large expansion area.

Another object of the invention is the provision of a multiple fuse plug, the casing of which is provided with removable 25 ends so that the fuses may be replaced.

These objects are accomplished by using an insulating casing provided with removable ends and supplying a threaded band 30 and a contact terminal connected by the fuse, in conjunction with each end, and mounting in the casing means for protecting one fuse when the other is blown, said means being provided with means for allowing 35 the expansion of gases generated by the blowing of a fuse throughout the whole casing.

These and other objects of the invention will be more clearly understood from the 40 following detailed description and accompanying drawings, in which—

Figure 1 is a vertical section through the fuse;

Figure 2 is an end view of the assembled 45 fuse;

Figure 3 is a section along the line 3—3, Figure 1;

Figure 4 is a section through a modification 50 of the fuse showing two removable ends.

Referring to the above-mentioned drawings, a casing 10 of insulating material is provided with a removable end 11. Each end of the casing 10 is threaded as at 12 and 13 and 55 has mounted thereon threaded metallic bands 14 and 15 which engage with the

threaded portions 12 and 13, respectively. The threaded metallic band 14 serves to retain the removable end 11 in position. Projecting through openings in each end of the 60 casing are spring arms of contact members 16 and 17.

The casing chamber is divided into two compartments 18 and 19 by means of a plate 20 which is mounted on a circumferential 65 shoulder 21 extending around the inner face of the casing and near its centre line. The plate 20 is provided with an opening 22 which allows communication between the compartments 18 and 19 thus allowing 70 greater expansion of the gases that may be generated upon the blowing of one of the fuses to be described later.

A fuse 23 extends through an opening 24 in the removable end 11 and connects 75 the contact member 16 with the metallic band 14. A drop of solder would preferably be used for attaching the end of the fuse 23 to the metallic band 14. A fuse 25 extends through an opening 26 in the wall of the 80 casing 10 and serves to connect the contact member 17 to the metallic band 15. The end of the fuse 25 is rigidly attached to the band 15 so as to retain the band in position on the casing 10. The plate 20 which is located between the fuses 23 and 25 serves to 85 protect one fuse from the other when either is blown.

A modification of the fuse is shown in Figure 4. In this case the casing 10' is 90 provided with two removable ends 11 and 27. The removable end 27 is retained in position on the casing by means of the metallic band 15. The remainder of the fuse is the same as described above. In order to 95 remove the end 11 the metallic band 14 is unscrewed. This gives access to the compartment 18.

The above description sets forth a multiple fuse plug so constructed that when 100 one fuse is blown disconnecting a circuit the fuse plug may be reversed, utilizing the other fuse to re-establish the circuit. This provides a simple and efficient multiple fuse that may be constructed at a cost but little 105 in excess of the cost of a single fuse.

I would state in conclusion that while the illustrated examples constitute practical embodiments of my invention I do not limit myself strictly to the exact details herein illustrated since manifestly the same can be considerably varied without departing from 110

the spirit of the invention as defined in the appended claims.

Claims:

1. A multiple fuse plug of the class described, comprising an insulating casing having removable ends, means for dividing the casing chamber into two compartments, said means being provided with an opening to allow communication between said compartments, threaded bands mounted on each end of said casing, retaining said removable ends in position, contact members projected through the ends of said casing, fuses located in each compartment, each fuse serving to connect the contact member extending into its compartment to the threaded band mounted on the same end of the casing as said contact terminal.
2. A multiple fuse plug, comprising a tubular casing of insulating material, a circumferential shoulder formed in the casing near its center, means for closing the end of the casing, means mounted on the shoulder dividing the casing into two compartments, and fuses mounted in each compartment.
3. A multiple fuse plug of the class described, comprising a casing of insulating material having both ends threaded and provided with removable end pieces, a circumferential shoulder formed in said casing, means mounted on said shoulder for dividing the casing chamber into two compartments, said means being provided with an opening allowing communication between the compartments, threaded metallic bands mounted on each end of the casing, said bands serving to retain the end pieces in position, contact members projected through the end pieces, and fuses, one mounted in each compartment, for connecting the contact member extending into its compartment with the threaded metallic band associated with the same end of the casing as the contact member.
4. A multiple fuse plug of the class described, comprising a hollow cylindrical casing having both ends threaded and provided with removable end pieces, threaded metallic bands for forming terminals

mounted on each end of the casing and serving to retain the end pieces in position, contact members projecting through said end pieces, a fuse connecting each contact member with the metallic band associated with the same end of the casing as the contact member, a circumferential shoulder formed on the inner wall of said casing, and a plate mounted on said shoulder dividing the casing chamber into two compartments, said plate having an opening extending therethrough for allowing gases to pass from one compartment to the other.

5. A multiple fuse plug of the class described, comprising a hollow cylindrical casing provided with removable ends and having both ends of its outer wall threaded, a threaded metallic band mounted on each end of the casing serving to retain the ends in position and forming terminals, contact members projected through each end of the casing, a fuse connecting each contact member to the metallic band associated with the same end of the casing, and a plate mounted in the casing and dividing the casing chamber into two compartments, said plate being provided with an opening for allowing gases expanding in one compartment to pass into the other.

6. A multiple fuse plug of the class described, comprising a hollow cylindrical casing of insulating material having removable ends, said casing having its outer surface threaded, threaded metallic bands mounted on each end of said casing serving to retain the movable ends in position, contact members projecting through each end, a fuse connecting each contact member with the metallic band associated with the same end of the casing, said fuses being detachably connected to the bands in a manner to prevent the removal of the bands from the casing, a circumferential shoulder formed on the inner face of the casing, a plate having an opening therein mounted on said shoulder, and means provided in conjunction with said plate for retaining it in position on the shoulder.

JAMES M. NEIDIG.
